STAMP SUPPORT

Richard O. Morgan, Evanston, Ill.

Application May 18, 1936, Serial No. 80,428

6 Claims. (Cl. 206—73)

This invention relates to a stamp support, and more particularly to a dispensing device for supporting a plurality of sheets of stamps of various denominations in such a position that they can be readily handled. The invention is particularly useful in connection with the use of sheets of pre-cancelled stamps.

An object of the invention is to provide stamp-supporting apparatus in which stamps of various denominations are rendered visible and easily accessible, means being provided for enabling the stamps to be readily torn off. A further object is to provide a stamp-dispensing device in which the last row of stamps can be readily removed, while at the same time being rendered visible. A further object is to provide a device for dispensing or supporting stamps or the like, in such a manner that they are prevented from curling under humid or other atmospheric conditions, and in which the stamp sheets are securely held against wind, draughts, etc. Other specific objects and advantages will appear as the specification proceeds.

The invention is illustrated in a preferred embodiment, by the accompanying drawings, in which—

Fig. 1 is a perspective view of a dispensing device embodying my invention, the dispensing device being provided with rows of stamps or the like; Fig. 2, a longitudinal sectional view, the section being taken as indicated at line 2—2 of Fig. 1; and Fig. 3, a perspective view of one of the dividers employed.

In the illustration given, a metal case A is provided with a bottom wall 10, having a rearwardly turned front edge 11. The case is also provided with a rear wall 12 and side walls 13.

The side walls 13 are provided with a plurality of spaced perforations 14, in which are mounted pivot rods 15, carrying the dividers 16.

The dividers 16 are each constructed, as shown more clearly in Fig. 3. That is, the front portion of the divider is struck upwardly to provide a shoulder 17. Just ahead of the shoulder 17, is a relatively wide flange 18, which is provided near one side with slots 19. Near one end of the shoulder 17, is a wire handle 20, which is welded within the curve of the shoulder. Secured to the rear portion of the dividers 16, are two spring strips 21, which have forwardly and upwardly extending free ends 22.

The dividers are assembled within the case A, as shown more clearly in Fig. 2. Between the lowermost divider and the bottom wall, and between each of the dividers thereabove, is sup-

ported a sheet of stamps 23. The stamps are illustrated as provided with suitable perforations, and at the front of each sheet of stamps, a row is folded back along its horizontal line of perforations. It will be observed that the front edge 5 of each of the dividers 16 tends to press the stamp forwardly, while at the same time the shoulders 17 press the stamp row rearwardly. The function of the shoulder 17, in this respect, is achieved by the front edge 11 of case A with respect to the 10 lowermost row of stamps.

On the side of the case, where the slots 19 appear, it will be observed that there is nothing to interfere with lateral movement of the stamps. On the opposite side, the wall 13 is provided with 15 a plurality of spaced notches 24, adapted to receive the handles 20.

In the operation of the device, sheets of stamps are placed between the dividers and between the lowermost divider and the bottom wall 10, as 20 shown more clearly in Fig. 2. The spring fingers 22 engage the rear edges of the stamp sheets and prevent them from falling into the back part of the case. At the same time, they maintain them 25 yieldingly in position within the divider compartment. The spring fingers are particularly useful when only a portion of the stamp sheet remains in the divider compartment. Such a sheet would tend to become dislocated, if it were not for the spring fingers. Preferably, there is secured between each of the dividers stamp sheets of different 30 denominations, so that there is presented to the operator a series of stamp rows of different denominations. For the purpose of illustration, case A has been shown with only a few dividers, 35 and therefore only a few stamp compartments. In practice, it is common to provide case A with a much larger number of dividers.

The operator, in applying the stamps to parcel post packages, etc., can readily grasp any stamp 40 of the desired denomination and tear it, the front edge of the divider serving as a firm, straight edge against which the tear is effected. In this manner, the vertical rows of stamps can be used. When a row has been completed, the operator 45 draws forward another row of stamps on the same sheet, and it is then caused to assume a vertical position between the forward edge of the divider and the shoulder or upwardly extending projection 17 on the divider therebelow. When 50 the last row of stamps is reached, it will be obvious that this cannot be drawn to a vertical position. These stamps are fed laterally by the operator pressing his finger through slots 19. The side edge of the divider forms a straight 55

edge against which the laterally moved stamps can be torn. When the last row has been fed laterally, and the last stamp removed, a new sheet may be inserted into the compartment and used up in the manner already described. It will be understood that a large number of stamp sheets can be supported in each compartment, and after the topmost sheet has been consumed, the next sheet may be drawn forward.

10 As shown more clearly in Fig. 2, the upwardly extending projection 17 of each divider is curved somewhat rearwardly so that there is a space between its bottom portion and the edge of the divider thereabove. As one of the dividers is lifted vertically, the edge of the divider thereabove is brought into engagement with the shoulder so as to provide a stop. However, the space is sufficient to permit raising each divider a sufficient distance to permit the insertion of sheets of stamps. Further upward movement is prevented, thus making it difficult for the operator to throw the rest of the stamp sheets out of position or location. In other words, the space between each divider front edge and the shoulder therebelow affords a limited vertical movement of the divider below, for the necessary insertion of sheets, but prevents a larger opening, which might result in the dislocation of sheets.

15 The rearwardly inclined angle of the shoulders or upward extensions 17 not only places the stamps at a convenient angle for tearing, but also supports the stamps in a position in which they can be readily seen by the user.

20 While in the construction shown, I have set forth certain specific details as being desirable, it will be understood that many of such details may be modified greatly, or even eliminated, and the construction can be considerably changed without departing from the spirit of my invention.

25 The foregoing detailed description has been given for clearness of understanding only and no unnecessary limitations should be understood therefrom, but the appended claims should be construed as broadly as permissible in view of the prior art.

30 I claim:

35 1. In apparatus of the character set forth for supporting sheets of stamps or the like, perforated to form rows, a casing, a plurality of stamp sheet-supporting dividers movably mounted in said casing in stepped relation, each of said dividers being provided with an integral upwardly extending shoulder cooperating with 40 the forward edge of the divider thereabove for maintaining a row of stamps in a substantially vertical plane, said dividers being provided, ad-

45 jacent their forward edges and near one side, with finger slots by which stamps confined between said dividers may be moved laterally.

2. In apparatus of the character set forth, a casing, a plurality of dividers movably secured to 5 said casing, said dividers providing between them compartments adapted to receive stamp sheets perforated in rows, each of said dividers being provided at a point spaced from its forward end with an upwardly extending shoulder, said shoulder 10 cooperating with the forward end of the divider thereabove for maintaining a row of stamps in a substantially vertical position.

3. In apparatus of the character set forth, a casing, a plurality of plate dividers movably carried by said casing, at least some of said dividers having a forward portion thereof folded upwardly to provide shoulders, said shoulders being spaced from the front edge thereof, said shoulder 15 cooperating with the front edge of the 20 plate divider thereabove to maintain a portion of a sheet in an angular position with respect to the remaining portion of the sheet.

4. In apparatus of the character set forth, a casing equipped with downwardly and forwardly 25 inclined sides, plate dividers pivotally supported in said sides and in stepped relation, each of said dividers being provided near its forward portion with an upwardly extending shoulder spaced a short distance ahead of the front edge 30 of the divider thereabove.

5. In apparatus of the character set forth, a casing equipped with downwardly and forwardly inclined sides, plate dividers pivotally supported in said sides and in stepped relation, each of 35 said dividers being provided near its forward portion with an upwardly extending shoulder spaced a short distance ahead of the front edge 40 of the divider thereabove, and each of said dividers having that portion ahead of the shoulder 45 provided near one side with a laterally extending finger slot.

6. In apparatus of the character set forth, a casing equipped with downwardly and forwardly inclined sides, plate dividers pivotally supported 45 in said sides and in stepped relation, each of said dividers being provided near its forward portion with an upwardly extending shoulder spaced a short distance ahead of the front edge of the 50 divider thereabove, and each of said dividers having that portion ahead of the shoulder provided near one side with a laterally extending finger slot, at least one side wall being cut away 55 to permit the lateral movement of sheets confined between said dividers beyond said cut away casing side.

RICHARD O. MORGAN.
